United States Patent Office.

ROLAN DAILY, OF CANAL TOWNSHIP, PENNSYLVANIA.

Letters Patent No. 67,781, dated August 13, 1867.

IMPROVED WASHING MACHINE.

The Schedule referred to in these Letters Patent and making part of the same.

TO ALL WHOM IT MAY CONCERN:

Be it known that I, ROLAN DAILY, of Canal township, of the county of Venango, and State of Pennsylvania, have invented a new and improved Washing Machine; and I do hereby declare that the following is a full and exact description of the same, reference being had to the accompanying drawings, and the letters of reference marked thereon.

Figure 1 is an end view of my machine with an end board removed to show the construction of the same.

A A are a "trough" or box, with a shoulder or "offset" at S S. 1, 2, 3, 4, 5, 6, 7, 8, 9, 10, 11, 12 are rollers with corrugations or cogs running their whole length. These rollers pass through a partition, W W, (see Figure 2, which is a top view of my machine,) on the ends of them, forming so many cogged wheels which "gear" into the large cogged wheel E. B B is an inside frame which rests on the "offset" S S, and in which are hung the cogged rollers 13, 14, 15, 16, 17, 18, 19. These rollers gear into the smaller cogged wheel D. F is a lever bolted on the wheel D; G is a "connection" between the lever F and the short lever H, (see fig. 2,) H being bolted on the wheel E.

On moving the lever F the wheels D and E made to perform about one-third of a revolution, thereby causing all the small rollers, from 1 to 12, and 13 to 19, to revolve "back and forth." The frame B B is fixed securely in its place by the screw C. The water is placed in the trough A A, and the clothes to be washed are laid down on the rollers 1-12, the frame B B of course being first removed. When the clothes are placed on the rollers 1-12 the frame B B is placed in the box A A, and the screw C turned securely, then the connection G or the lever F is placed over the short lever H, thus connecting the two wheels D and E, when a forward and back motion is given to the lever F, causing both sets of rollers, 1-12 and 13-19, to revolve, thus rubbing the clothes and cleansing them effectually.

What I claim as my invention, and desire to secure by Letters Patent is as follows, to wit:

I claim the box A A, in combination with the corrugated rollers 1-12, the frame B B, in combination with the rollers 13-19, and the wheels D E, when the same are constructed as described in the aforesaid combination for the purposes set forth.

ROLAN DAILY.
